Attorneys.

UNITED STATES PATENT OFFICE.

GEORGE F. LOUGHREN, OF BOSTON, MASSACHUSETTS, ASSIGNOR OF ONE-HALF TO
FREDERICK C. LANGENBERG, OF CAMBRIDGE, MASSACHUSETTS.

LOCK FOR FOUNDRY FLASKS.

Application filed November 1, 1922. Serial No. 598,307.

To all whom it may concern:

Be it known that I, GEORGE F. LOUGHREN, a citizen of the United States, residing at Boston, county of Suffolk, State of Massachusetts, have invented a certain new and useful Improvement in Locks for Foundry Flasks, of which the following is a specification, reference being had therein to the accompanying drawings.

10 This invention relates more particularly to locks to fasten together the sides of the ordinary types of molders' snap flasks used in metal casting. Due to the fact that these flasks must be handled and operated largely by unskilled labor, it is necessary to make their construction as simple as possible consistent with the accomplishment of the results desired.

15 The purpose of my invention is to provide a lock for one corner of each part or section or the ordinary type of hinged snap flask, which can be easily operated by unskilled labor and which can under no circumstances become accidentally unfastened.

20 25 30 35 40 45 The customary types of locks used on molders' flasks have been in many respects unsatisfactory. It has been found under present working conditions that the locks, which have been used, would become unfastened and cause the mold, in the process of being formed, to be injured or entirely spoiled.

Molding machines have largely replaced the old method of ramming sand into the flask by hand. These molding or jarring machines are constructed so as to cause the flask, which is placed thereon, to be violently jarred up and down for the purpose of forcing the sand to properly adjust itself to form the mold. It is under such conditions particularly that the old types of locks have proved unsatisfactory. My invention, therefore, consists in a lock, which not only can be easily engaged and disengaged, but which will not become unfastened under the above described working conditions.

45 50 The invention will be fully understood from the following description when taken in connection with the accompanying drawings, and the novel features thereof will be pointed out and clearly defined in the claims at the close of this specification.

In the accompanying drawings, Fig. 1 is a plan view of one part, or section, of an

ordinary type of hinged molders' flask with 55 my locking device attached thereto.

Fig. 2 is a side elevation showing the lock of my invention.

Fig. 3 is a perspective view of a two-part molder's flask, the cope and drag being 60 placed together in the manner employed in making molds. My invention is shown attached to each of these parts or sections.

Similar letters of reference indicate the 65 same parts in all of the figures.

A, B, C, and D, denote the sides of one part or section of a molder's flask, the sides A and B being permanently attached together at one corner and the sides C and D being attached in a similar way at the diagonally opposite corner. In Figure 1, the sections formed by sides A and B, on the one hand, and C and D, on the other, are hinged together at E.

Attached to the corner of each part or section of the flask, diagonally opposite the hinged point E, is shown, in Figure 1, my locking device, indicated as F. The locking device F consists of two lug members G and H. These lug members are attached, 75 80 by means of screws or other suitable means, to the sides B and C respectively, of each part or section of the flask. The lug member G has two lugs a and b, which may be clearly seen in Figure 2 of the drawing. 85

The lug member H has also provided thereon two lugs similar to those attached to the lug member G. These lugs are indicated in Figure 2 as c and d. The lower lug c has a hole which registers with the corresponding hole in the lug b, and the lug d has a similar hole which registers with the hole in the lug a. The lug d is also provided with a hole e through which passes a vertical portion of a slidable latch K. The 95 latch K is provided with a spiral spring L, around the above mentioned vertical portion, and a pin m. The spring L is supported by the pin m at the lower extremity of the spring. The upper end of said spring 100 bears against the lower face of the lug d.

The purpose of this spring is to exert pressure downward, at all times on the latch K. The latch K is formed with two offset portions constituting bolts or pins, indicated in Figure 2 as g and f, so disposed that when a part or section of the flask is brought into a closed position and the holes of the four

2
lugs are brought into register, as above pointed out, the pins *g* and *f* will enter the holes in the lugs *d* and *a*, and *c* and *b*, respectively.

5 It is clear from the above description that when the latch *K* is so engaged in the lugs *a*, *b*, *c*, and *d*, no amount of jarring, due to the placing of the device on a molding machine, will be sufficient to cause the locking device to become disengaged. This desirable result is accomplished by reason of the fact that the latch is held firmly in an engaged position by the spring *L* and, in addition, is assisted by the force of gravity 10 which tends to keep the bolts or pins *j* and *g* so engaged.

It is also to be observed that my latch, because of the presence of the two pins or bolts, forms a more secure lock for each part 15 or section of the flasks than has previously been provided. It is clear that the two adjacent sides of each part or section, which are to be locked, are very satisfactorily held together because the pin or bolt *g* engages the lugs *d* and *a* near the upper edge of the adjacent sides and the pin *f* engages the lugs *c* and *b* near the lower edge. These bolt portions *g* and *f*, being parts of the same latch member *K*, may be simultaneously released 20 by a relatively small movement of the latter, this movement being readily permitted even in the case of assembled flask sections, as shown in Figure 3.

Modifications in the details of the device 25 described may be made without departing from the spirit of my invention or sacrificing any of its advantages.

Having thus described the invention, what I claim as new is:—

40 1. In a molder's flask, the combination with the four sides and corners, of a hinged connection at one corner, and a lock at the diagonally opposite corner, said lock comprising lug members secured to adjacent sides of said flask respectively, and a vertically 45 slideable bolt movable to engage and disengage both of said lug members.

2. In a molder's flask, the combination 50 with the four sides and corners, of a hinged connection at one corner, and a lock at the diagonally opposite corner, said lock comprising lug members secured to adjacent sides of said flask and provided with lugs, each lug of one lug member having a hole 55 registering with a corresponding hole in a lug of the adjacent lug member, and a vertically slideable latch adapted to enter said registering holes.

3. In a molder's flask, the combination 60 with the four sides and corners, of a hinged connection at one corner, and a lock at the diagonally opposite corner, said lock comprising lug members secured to adjacent sides of said flask and provided with lugs,

each lug of one lug member having a hole 65 registering with a corresponding hole in a lug of the adjacent lug member, and a vertically slideable latch, guided in one of said lug members, and having upper and lower pins adapted respectively to engage the upper and lower lugs of the said lug members. 70

4. In a molder's flask, the combination with the four sides and corners, of a hinged connection at one corner, and a lock at the diagonally opposite corner, said lock comprising lug members secured to adjacent sides of said flask and provided with lugs, each lug of one lug member having a hole 75 registering with a corresponding hole in a lug of the adjacent lug member, and a vertically slideable latch, guided in one of said lug members, having upper and lower offset portions or pins, adapted respectively to engage the upper and lower lugs of the said lug members, said latch having a spring to assist 80 in holding it downward in the engaged position. 85

5. In a molder's snap flask, the combination with the four sides and corners, of a hinged connection at one corner, and a lock at the diagonally opposite corner, said lock comprising lug members secured to adjacent sides of said flask and provided with lugs, each lug of one lug member having a hole 90 registering with a corresponding hole in a lug of the adjacent lug member, and a vertically slideable latch guided in one of said lug members, having upper and lower offset portions or pins, adapted respectively to engage the upper and lower lugs of the said lug members, said latch having a vertical portion, a spiral spring around said vertical portion, and a pin positioned in said vertical portion, one end of said spring resting on said pin and the other end of said spring resting on the lower face of one of said lug members to assist in holding said latch 95 downward in the engaged position. 100

6. In a molder's flask, the combination with the four sides and corners, of a hinged connection at one corner, and a lock at the diagonally opposite corner, said lock comprising lug members secured to adjacent sides of said flask respectively, and a longitudinally slideable bolt to engage and lock 110 the lug members of the adjacent sides together. 115

7. In a molder's flask, the combination with the four sides and corners, of a hinged connection at one corner, and a lock at the diagonally opposite corner, said lock comprising lugs on each of two adjacent sides at points adjacent the upper and lower edges thereof and a slideable bolt having portions to lock each of said lugs to a corresponding lug on the adjacent side. 120

In testimony whereof I affix my signature.
GEORGE F. LOUGHREAN.
